UNITED STATES PATENT OFFICE.

JOSEPH CONCKLEN COOPER, OF BROOKLYN, NEW YORK.

COMPOSITION FOR TREATING FUEL.

SPECIFICATION forming part of Letters Patent No. 424,961, dated April 8, 1890.

Application filed February 14, 1889. Serial No. 299,896. (No specimens.)

To all whom it may concern:

Be it known that I, JOSEPH CONCKLEN COOPER, of Brooklyn, county of Kings, and State of New York, have invented certain new and useful Improvements in Fuel Compositions, for insuring the practically perfect combustion of the same, fully set forth in the following specification.

This invention relates generally to a composition adapted for use with carbonaceous fuel to insure the complete combustion thereof and prevent the waste of heat which now occurs by reason of the necessity of employing strong drafts in order to cause a sufficient volume of oxygen to be supplied to the fuel to aid its combustion.

The object, therefore, of the present invention is to provide for the more perfect combustion of fuels and the utilization of their heat values by adding substances thereto which shall insure the complete combustion of the gases (carbonic oxide and sulphur) with the admission of less atmospheric oxygen, and that will produce from a given amount of carbon fuel a greater volume of heat, or a given amount of heat, from the use of less fuel, while reducing the destructive effect of sulphur and other gases on the metal or other surfaces exposed to the action of the heat.

I am aware that it has been proposed to use various fire-kindling and fuel compounds—such as a mixture of chloride of sodium, nitrate of potash, and sulphate of iron; of starch, 35 nitrate of soda, and sulphate of aluminium; of Glauber's salts and wood ashes; of chloride and sulphate of soda and muriate of ammonia and water, and of chloride of sodium and sulphate of soda—but long experience 40 with these compounds has failed to attach any great value to them on account of the difficulty in handling some of the ingredients, their bulky nature, cost, and liability to be rendered valueless by contact with an alkali, 45 such as potash.

In Patent No. 279,479, granted to me June 12, 1883, there is set forth and claimed a composition composed of alumina as contained in alums, aluminous cake, or earths, chloride 50 of sodium, and sulphate of soda, which, so far as my experience and observation goes, went far to overcome the difficulties encountered

in using the old compounds; but it needed intelligent use, which, owing to the various conditions under which it was used, it seldom got. 55

In the practice of my invention I use a compound which in practical use demonstrates the possibility of consuming carbonaceous fuels with a minimum of draft or atmospheric oxygen, preventing the waste ordinarily incurred 60 by heating large volumes of air not practically needed for combustion by the escape of large heat values in the form of carbonic gases not receiving the equivalent of oxygen necessary to form complete combustion without the aid of a compound adapted to insure 65 the same, and the waste and destruction of furnace-linings and metal surfaces from the corroding or destroying action of the sulphur contained in the coal. 70

In the practice of my invention I take chloride of sodium or common salt. I also take aluminium, preferably sulphate of alumina, as contained in the alums of commerce or aluminous cake or earths. I also take potassium in the form of carbonate of potash, at present for the sake of economy in preparation using potash, pearlash, or sal-tartar, (not using any nitrate form of these ingredients.) These are combined in varying and 75 variable proportions, according to the character of the fuel or the method of using it; but for the ordinary combustion of coals or other carbonaceous fuels I prefer to take of common salt, by weight, five or six parts; of the 80 alums or aluminous cakes or earths, two parts; of potash, if nearly pure in carbonate form, one part. I mix these together reduced to as fine a powder as possible, and if necessary prevented from caking or becoming hard 85 by adding some coal-dust, ground coal, or other suitable material for that purpose. 90

I apply the compound dry by sprinkling it over the carbonaceous fuel or dissolve it in water for convenience of application, and use 95 it in the proportion of, say, twenty-four (24) ounces to forty-eight (48) ounces to each ton of carbonaceous fuel, making the application as complete and uniform as possible. The application of the compound may be made at 100 any time before using the fuel from five minutes to a year, if the fuel after the application is sheltered from the action of the elements.

When the fuel is treated with this compound

and ignited, a much greater flame is caused, showing its prompt action on the gases evolved in the combustion of the fuel; the heat properties of the fuel are all availed of; the waste in the escape of unconsumed gases is greatly diminished, owing to the fact that much less draft is necessary to support combustion, and by its fluxing qualities the fuel is entirely consumed, leaving finer and lighter ashes free from clinker as the result. By aiding the first ignition of the fuel it enables heat to be produced more quickly, and as the quantity of atmospheric oxygen can be greatly reduced and the dampers and air-drafts closed or considerably restricted, the heat is thereby utilized and its escape in the outlets greatly reduced. I also find that this compound reduces the smoke of bituminous coals, and that all metallurgical operations—such as smelting from the ores, melting in furnaces or elsewhere—are greatly facilitated by its action,

cleaner metal and of a better quality being the effect.

In all kilns or similar appliances the action of this compound is effective by reason of the greater flame and heat produced and the freedom of the same from deleterious gases, which ordinarily are so destructive and damaging in their effect—as, for instance, in potteries, brick and lime kilns, and similar works. 25 30

What I claim is—

The herein-described compound for treating fuel, the same consisting of a mixture of chloride of sodium, sulphate of alumina, and carbonate of potash. 35

In testimony whereof I have signed my name to this specification in the presence of two subscribing witnesses.

JOSEPH CONCKLEN COOPER.
